UNITED STATES PATENT OFFICE

158,652

BICYCLE

Edgar L. Dailey, Atlanta, Ga.

Application December 11, 1947, Serial No. 143,104

Term of patent 3½ years

(Cl. D90—8)

To all whom it may concern:

Be it known that I, Edgar L. Dailey, a citizen of the United States, residing at Atlanta, in the county of Fulton and State of Georgia, have invented a new, original, and ornamental Design for a Bicycle, of which the following is a specification, reference being had to the accompanying drawing, forming part thereof.

The figure is a perspective view of a bicycle, showing my new design.

The dominant features of my design have been indicated in solid lines in the drawing.

I claim:

The ornamental design for a bicycle, as shown and described.

EDGAR L. DAILEY.
